UNITED STATES PATENT OFFICE.

ALBERT SIMON JOHAN VAN KESTEREN, OF VLASSINGEN, NETHERLANDS.

TELEPHONE TRANSMISSION SYSTEM WHEREIN REINFORCING-REPEATERS ARE EMPLOYED.

1,189,411.

Specification of Letters Patent.

Patented July 4, 1916.

Application filed December 19, 1913. Serial No. 807,749.

To all whom it may concern:

Be it known that I, ALBERT SIMON JOHAN VAN KESTEREN, a subject of the Queen of the Netherlands, and residing at Vlissingen, Province of Zeeland, Netherlands, have invented certain new and useful Improvements in and Relating to Telephone Transmission Systems Wherein Reinforcing-Repeaters Are Employed, of which the following is a specification.

This invention relates to telephone transmission systems comprising repeaters for reinforcing the current waves between two subscribers' stations.

According to this invention, a long distance line for conversation in each direction between the stations is provided, which two lines are connected at their ends to each other and also to lines leading to each subscriber's station, the latter connections being positive or inductive, while the total damping of the two lines between the points of connection is made equal to, or greater than the total reinforcing produced by the repeater or repeaters. This arrangement allows conversation in both directions to be carried on, without it being necessary to balance portions of the lines, or use reversing switches.

Figure 1 of the accompanying drawing shows diagrammatically an unsuitable system subject to the so-called buzzing or howling. Fig. 2 shows a system according to this invention, with one repeater for each talking direction. Fig. 3 shows a system with several repeaters for each talking direction. Fig. 4 shows a system according to this invention, with one relay only for both directions of talking.

In the system according to Fig. 1, which has not proved satisfactory in practice, the repeaters T_3 , T_4 are inserted in the line $c-c$ at a point intermediate the talking stations C and D. It was held that the talking current produced at station C, is strengthened by the repeater T_3 , so that it becomes audible at station D, and that the talking current produced at D, is strengthened by the repeater T_4 , so that it becomes audible at station C. It has been found, however, that the action is different. The talking current emanating from T_3 divides at the junction x , and one portion reaches the receiver a_4 of the repeater T_4 , appears strengthened at b_4 and divides at the junction y , part then going

through a_3 into the repeater T_3 and being transmitted reinforced to b_3 , and so on. The result is that buzzing is heard in the receivers of the subscribers' stations, and the system is unsatisfactory.

Fig. 2 shows a system according to this invention. In a long distance line comprising the parts L_4 and L_1 a repeater T_1 is inserted of which a_1 is the receiving and b_1 the transmitting side. The repeater T_1 thus transmits talking currents only in the direction from station A to station B. The second line L_2 and L_3 transmits talking currents only in the direction from B to A, as the repeater T_2 is arranged with its receiving side a_2 connected to station B, and its transmitting side b_2 connected to station A. At points p and q the sending and receiving lines are connected to each other and to lines leading to the subscribers' stations. The connections to these latter may be either direct or inductive. The lines $q-A$ and $p-B$ may be themselves long distance lines, so that the points p and q need not be near the subscribers' stations. The repeaters T_1 and T_2 are connected in the long distance lines at any desired points, and the lines may each follow any desired path. Conversation in this system can be carried on in both directions, provided that, according to this invention, the total reinforcing by the repeaters T_1 and T_2 is equal to, or smaller than, the total damping by the long distance lines L_1 , L_2 , L_3 , L_4 . No buzzing currents, such as appear in the system shown in Fig. 1, will appear in the system shown in Fig. 2, as any current wave circulating in the circuit q , L_4 , T_1 , L_1 , p , L_2 , T_2 , L_3 , q rapidly diminishes to zero value, as it is being constantly damped to a greater extent, than it is reinforced.

If the damping in the line L_2 , L_3 should be smaller than the reinforcing in said line then, in order that there should be no inadmissible howling currents, the reinforcing in the line L_4 , L_1 must be smaller by at least the same extent than the damping in the same line. In this case, at the point q talking currents arrive which are stronger than those set out from the point p . At the point p , on the contrary, currents are received which are weaker than the currents sent out from the point q .

It follows from the foregoing that the lines L_1 , L_4 and L_2 , L_3 need not be balanced.

As the talking currents passing through the points p or q , after having passed through the long distance lines, are received at the points q or p with little or no weakening, the lines between A and q or between B and p may be of considerable length.

Fig. 3 shows an arrangement in which a number of repeaters T_5 and T_6 are inserted at arbitrary points in the long distance lines 10 L_5 and L_6 . The above mentioned rule applies also here, so that the total reinforcing by the repeaters T_5 and T_6 may at the outside be equal to the total damping in the lines L_5 and L_6 between the points p and q . 15 Fig. 4 shows a system in which the reinforcing can be effected by means of a single repeater. In this arrangement it is necessary to insert the repeater T_7 between two long distance lines L_7 and L_8 at such a distance from the junction points p and q that neither of the two circuits on the right and left hand side of the repeater T_7 , the damping will be smaller than the reinforcing. 20 These two circuits of course need not be balanced. If the damping of the current waves in one of the two circuits situated laterally of the relay T_7 , were less than the reinforcing by the repeater T_7 , howling would take place, as described above with 25 reference to Fig. 1. Apart from the fact that the system of Fig. 4 is not so good as the system of Figs. 2 and 3, owing to the situation of the repeater T_7 being incapable of much variation, the system of Fig. 4 is 30 less efficient than the first described two systems.

The double wire lines illustrated may be obviously replaced by single wire lines with earth return, without departing from the invention, and the invention can be used 40 in systems other than those diagrammatically illustrated.

Having thus described my invention, what I claim is:—

1. In a telephone system comprising at 45 least one repeater for strengthening the current waves between two subscriber stations, a line for conversation in each direction between said stations, the said separate lines being electrically connected at the ends to 50 each other and also to each subscriber's station, the said lines being of such extent that the damping therein between the two points of connection is equal to, or greater than, the total strengthening produced by the repeater. 55

2. A telephone transmission system comprising in combination, a pair of parallel lines connected at the ends to each other and also to lines going to each subscriber's station, and repeaters placed in said lines and so arranged that one line is used only for transmission in one direction and so that the total damping in a closed circuit composed of said parallel lines is greater than 60 the total reinforcing of the repeaters. 65

In testimony whereof I affix my signature in presence of two witnesses.

ALBERT SIMON JOHAN VAN KESTEREN.
